UNITED STATES PATENT OFFICE.

EDWARD J. BRANDT, OF WATERTOWN, WISCONSIN, ASSIGNOR TO BRANDT AUTOMATIC CASHIER COMPANY, OF WATERTOWN, WISCONSIN.

VARIABLE-THROW KEY FOR CALCULATORS.

Application filed May 8, 1919. Serial No. 295,521.

To all whom it may concern:

Be it known that I, EDWARD J. BRANDT, a citizen of the United States, residing at Watertown, in the county of Jefferson and State of Wisconsin, have invented certain new and useful Improvements in Variable-Throw Keys for Calculators, of which the following is a specification, reference being had therein to the accompanying drawing.

10 The invention relates to improvements in a variable throw operating mechanism, and although particularly adapted for use in connection with calculating machines, cashiers or registers, is capable of use in any field where such a mechanism is found to be desirable.

15 It is an object of the invention to provide a mechanism embodying a plurality of keys with differently formed actuating portions, the keys when actuated being adapted to co-operate with suitable operating means to move said means variable distances, the extent of movement of the operating means depending upon the formation of the actuating portion of the key that has been depressed. The actuating keys preferably have cam engaging portions of variable widths and adapted when shifted to engage and move an operating means, the length of 20 movement of the operating means being dependent upon the width of the cam portion of a key that has been actuated to control the mechanism with which the operating means is connected.

25 A further object of the invention is to provide an actuating key with a cam engaging portion having a gentle or slight curve to impart to the operating means with which it is associated upon the actuation of the key an easy start and a continued gentle movement during the entire stroke of the key, thus eliminating any shock or sudden blow incident to the operation of the older types of keys wherein said keys are formed 30 with wedge shaped engaging portions.

In a more specific embodiment the invention comprises a plurality of calculators or indicating elements, each designating the respective numbers of various denominations of money required, and associated keys having variable cam portions for actuating suitable operating means connected with the indicators, whereby upon a single stroke of a key the indicator of a certain denomina-

tion may be moved a number of digits if the total is such as to require a plural actuation of a particular denomination indicator. It is to be understood that by plural actuation it is meant that a given indicator may be moved more than one digit forward upon a single stroke of the operating key that is formed with a cam portion of a sufficient width to impart to the operating means of an indicator a movement that will actuate the indicator in plural. In carrying out the invention the cam portions of the keys are of different widths relative to each other, and if the cam or cams of a key are relatively narrow, then these cams when depressed move the operating means only a sufficient distance to cause the operating means to move the indicator one digit but on the other hand, if a key having a relatively broad cam is depressed then the length of movement imparted to the operating means is sufficient to move the indicator two or more digits, this of course, depending upon the width of the key depressed.

In the accompanying drawings I have shown the invention as being applied to a wage adder or calculator, but it will of course be understood that this disclosure is only for the purpose of illustration and that the variable cam mechanism forming a salient feature of the invention can be used wherever such a structure is desirable, especially in the art of cashiers, registers or similar machines.

In the drawings:

Figure 1 is a longitudinal sectional view. 90
Figure 2 is a rear elevation with parts in section.

Figures 3, 4 and 5 are detail views.

Referring now more particularly to the drawings wherein like reference characters 95 indicate corresponding parts, the numeral 1 designates a casing having a bottom 2 which may be of any conventional formation and formed with the appropriately marked sight openings 3 through which the totals of the indicators or adding wheels 4 and 5 mounted upon the shaft 5' are visible.

For the purpose of illustrating the invention I have shown the indicating mechanism as consisting of adding wheels 4 and 5, these wheels being arranged in sets of which the wheel 4 is known as the primary

wheel and the wheel 5 the secondary wheel. The casing is marked adjacent each sight opening with a numeral designating the denomination of the bill that the respective 5 indicators are totaling, the present machine having indicators for one dollar bills, two dollar bills, five dollar bills, ten dollar bills and twenty dollar bills. Of course any coin indicators may also be used and as a 10 matter of fact usually are, in this event the casing would be suitably marked adjacent a sight opening to indicate the denomination that a certain set of adding wheels is totaling. The adding wheels or indicators 15 4 and 5 are shown as being loosely mounted upon the shaft 5', and their sides rest against the friction pads 4' that are composed of leather or any other suitable material and secured to the web 6 keyed 20 to the shaft and adapted to rotate therewith. The peripheral portions of the adding wheels are formed with ratchet teeth 6' and each adding wheel has an outstanding flange portion 7 upon which are placed numerals ranging from 00 to 99, a set of 25 wheels being therefore capable of indicating through the sight opening any number up to and including 9999.

The adding wheels are maintained in 30 frictional relation with the pads 4' by means of the spiders 9 that are fastened to the shaft and carrying in the widened head portions thereof staggeredly arranged oppositely disposed spring pressed plungers 10 contacting with the sides of the adding wheels 4 and 5 and forcing the same into frictional contact with the friction pads 4' secured to the disk. As before stated, the indicator 4 of each set is known 35 as the primary indicator, while the indicator 5 is the secondary indicator. The indicator 4 is actuated in a step by step movement by a mechanism which will be later described and to carry over from the primary 40 wheel to the secondary wheel after the primary wheel has made a revolution, any suitable construction may be used, but for the purpose of illustration the structure I have shown consists of the pivoted pawl 45 50 12 having an elongated slot receiving the pivot pin 12' and provided with an upstanding part 13 which is disposed in the path of and adapted to be engaged by the lug 14 on the primary wheel, which forces the ratchet forward one step and correspondingly moves the secondary wheel forward one full number upon each revolution of the primary wheel. After the secondary 55 wheel has been shifted by the pawl the same 60 is returned to its normal position by the spring 15, it being understood that the pawl is normally forced upwardly toward the axis of the secondary wheel by the spring 15'. The registering mechanism herein 65 shown and described is merely for the pur-

pose of illustrating a convenient form of mechanism that may be operated by the operating means forming this invention and which will be presently described. The registering mechanism herein shown is the 70 subject matter of my application filed April 19, 1919, Serial No. 291,208.

Each set of indicators is provided with its operating means, and a description of one particular operating means and its associated actuating mechanism will be described, as it is believed that this will suffice for all. The primary wheel 5 is moved forwardly by the movable operating rod 16 located in the bottom of the casing and connected with the flap 17 intermediate its ends by the pivot 18. The lower end of the flap is pivoted to the casing as at 19 and is provided with a slightly offset rounded head portion 20 that is engaged and shifted by 80 the key cams in a manner which will later be described. The operating mechanism is positioned below the fixed ledge in the casing and the rod 16 has intermediate its ends an upstanding pawl 20' cooperating 85 with the ratchet teeth on the primary wheel 5 to move the primary wheel upon the actuation of the operating rod 16. The rod 16 passes through a suitable guide 21 extending upwardly from a base 22 positioned 90 beneath the axis of the indicating wheels, and the pawl or dog 20' is normally maintained in contact with the ratchet teeth of the primary wheel by the tension of the spring 22' attached to the end of the extension 22a of the rod 16 and to the casing. The front end of the flap 18 is, as before stated, rounded and offset somewhat beyond the vertical plane of the relatively 95 straight portion of the flap and when engaged and shifted by the actuating means which will be later described, moves on its pivot 19 thereby imparting a movement to the operating rod 16 causing the pawl 20' carried thereby and in engagement with the 100 ratchet teeth on the primary wheel 5 to be moved forward, moving the primary wheel one or more digits forward, depending of course upon the extent of movement or throw imparted to the rod 16, which throw 105 must be variable if the adding wheel is to be capable of being moved a single digit, or a plurality of digits upon a single movement of the operating means. When the rod 16 is moved by the depression of the key the spring 21' will be placed under tension so that when the key is released the spring will return the rod to its normal inoperative position.

To provide a variable throw for the operating means a plurality of keys 23 are employed having the usual finger caps 24 disposed exteriorly of the casing and adapted to bear various total amounts which it is intended shall be ultimately indicated 110 115 120 125 130

- in its fractional currency denominations by the different sets of indicators 4 and 5. The keys are normally maintained in the position disclosed in Figure 1 by the springs 5 24' coiled around a portion of each key having one end engaging a suitable shoulder on the key and its other end seated upon a ledge 25 fixed to the casing. Each key has a movable bar portion 26 located below the ledge 25 usually carrying a plurality of cams of variable widths, the formation of the cams being such as to move the proper fractional currency denomination indicators the required steps whether 10 singular or plural to indicate a total in fractional currency denominations equal to the denomination indicated on the key when the cams cooperate with the flaps 18 upon the actuation of the keys. The finger pieces 15 24 of the keys, as before stated, each bear thereon various total amounts which it is intended shall be ultimately indicated in its fractional currency denomination, and for example I have designated the key A 20 25 as bearing on its cap the numeral 89 to be divided by the machine and indicated as four twenty dollar bills, one five dollar bill and four one dollar bills, which will require the plural operation of the one and twenty 30 dollar indicators and a single operation of the five dollar indicator. To this end the movable bar 26 carries a plurality of cams A, B and C, the cams A and B being relatively wide, or as a matter of fact approximately 35 four times as wide as the cam C. For the purpose of illustration the twenty dollar cam A, as well as the one dollar cam B is divided by the vertical lines *a*, *b*, *c* and *d*, the width of each of these cams 40 to the first line *a* being sufficient to move the pivoted flaps 18 a distance that will move the operating rods 16 a sufficient length to impart to the primary wheels 5 a movement of one full digit, it being 45 obvious that as the key is depressed the twenty dollar indicator will be moved four steps by the wide cam A after the flap has ridden entirely across this cam, while the one dollar indicator will likewise be 50 moved four steps by the cam B, cooperating with its flap 18, which cam is of a width equal to the width of the cam A. The cam C is relatively narrow and the movement of the key will cause this cam to engage 55 its flap 17 moving the flap only a short distance about its pivot until the rounded head portion thereof leaves the influence of the curved surface of the cam riding out of contact with the same and the continued 60 movement of the key only causes the flap 17 to ride up the straight side of the cam C, at which time the one dollar and twenty dollar cams A and B are continuing to exert a driving influence upon their flaps 65 17 due to the long cam surface of each of these cams. As the flap 17 engages the twenty dollar cam A upon its depression, when the rounded head reaches the line *a* the operating rod 16 has been moved sufficiently to move the primary indicator one 70 digit, the continued movement of the cam until the flap 17 coincides with the line *b* serving to move the rod sufficiently to impart a two digit movement to the primary wheel and this continues until the rounded end of the flap 17 has reached or is passing beyond the influence of the lowest end of the cam, at which time the primary wheel has been shifted four full digits. 75 It will be understood that the flaps 17 extend entirely across the machine, one flap co-operating with all of the twenty dollar indicators, another with the ten dollar indicators, etc., so that upon the operation of the various keys the movable bar portions 26 thereof all carry differently formed cams so that the shifting of one key will move the flaps 17 of the different denomination indicators a greater or a less distance than the shifting of another key which will cause the operation of a denomination indicator in plural if the total requires this, or if the operation of the denomination indicator is only required in the singular, then the cam of the selected key is relatively narrow and shifts its flap a distance sufficient to move the indicator a single step. The variable cams are preferably integral with their movable ledge 26, and are formed to operate the flaps 17 a distance sufficient to move its indicator from 80 one to four digits, this depending upon the width of the cam. The cams have gentle or slightly curved engaging portions co-operating with the flap 17 so that when any one of the cams is brought into operation the flap will be given a gentle and easy start, and its movement will be one of this character throughout the stroke of the operating key, eliminating any sudden shock or blow incident to the operation of the older wedge 85 shaped operating portions on the keys. 90 In the specification and drawings I have described the invention as being embodied in a wage adder, but it will be understood that the variable cams and their associated operating mechanisms constitute the subject matter of this application, and I wish it to be distinctly understood that the invention is intended for use in any field where such a structure is found desirable. 95 Having thus described my invention, what I claim is:
1. A machine of the character described comprising an indicator, a flap pivotally connected to the machine and having an enlarged rounded upper end, means connecting the flap and indicator, and means adapted to engage the rounded upper end of the flap for operating the same. 105
  2. A machine of the character described 110
  3. A machine of the character described 115
  4. A machine of the character described 120
  5. A machine of the character described 125
  6. A machine of the character described 130

comprising an indicator, a flap pivotally connected to the machine and having an enlarged rounded upper end, means connecting the flap and indicator, and a cam adapted to engage the rounded end of the flap for operating the same.

3. A machine of the character described comprising an indicator, a flap pivotally connected to the machine and having an enlarged rounded upper end, means connecting the flap and indicator, and a cam adapted to engage the rounded end of the flap for operating the same, the engaging portion of the cam being inwardly curved from its lower end towards the upper end to cooperate with the rounded upper end of the flap to give a smooth steady movement to the flap upon the movement of the cam.

4. A machine of the character described comprising an indicator, a flap, said flap having its upper edge rounded to form an enlargement and its lower edge formed into an eye-portion, means connecting the flap

and indicator, means passing through the eye portion for pivotally connecting the flap, and means adapted to engage the enlargement on the upper edge to operate the flap.

5. A machine of the character described comprising an indicator, a flap, said flap having its upper edge rounded to form an enlargement, its lower edge formed into an eye-portion, and provided intermediate the upper and lower edges with a longitudinally extending eye, means extending through the eye-portion on the lower edge for pivotally connecting the flap to the machine, means connected to the intermediate eye and engaging the indicator, and means adapted to engage the enlargement on the upper edge of the flap to swing the same upon its pivot.

In testimony whereof I hereunto affix my signature in the presence of two witnesses.

EDWARD J. BRANDT.
